US0D1089131S

(12) **United States Design Patent** (10) Patent No.: **US D1,089,131 S**
(45) Date of Patent: **** Aug. 19, 2025**

(54) **INSPECTION EQUIPMENT CONTROL DEVICE**

(71) Applicant: **SHIMADZU CORPORATION**, Kyoto (JP)

(72) Inventor: **Hyeri Kang**, Kyoto (JP)

(73) Assignee: **SHIMADZU CORPORATION**, Kyoto (JP)

(**) Term: **15 Years**

(21) Appl. No.: **29/846,173**

(22) Filed: **Jul. 14, 2022**

(30) **Foreign Application Priority Data**

Apr. 27, 2022 (JP) ..... 2022-009238 D

(51) **LOC (15) Cl.** **13-03**

(52) **U.S. Cl.**

USPC **D13/162**; D13/184; D14/314

(58) **Field of Classification Search**

USPC D13/101, 103, 107, 110, 112, 114, 119, D13/122, 123, 133, 153, 154, 155, 156, D13/157, 160, 182, 184, 199; D14/300, D14/308, 439, 440, 314; D24/107, 158, D24/160

CPC G05B 2219/35001; G05B 2219/37351; H04N 7/183; G06T 7/0002; G06T 2207/10016; G06T 11/00; G06V 40/172; B01L 3/502715

See application file for complete search history.

(57) **CLAIM**

The ornamental design for an inspection equipment control device as shown and described.

DESCRIPTION

FIG. 1 is a perspective view of an inspection equipment control device showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 7 Drawing Sheets
